United States Patent Office.

WILLIAM DAVIDSON, OF BINGHAMTON, NEW YORK, ASSIGNOR TO HIMSELF AND WILLIAM J. RANNIE, OF THE SAME PLACE.

Letters Patent No. 71,712, dated December 3, 1867.

IMPROVED MEDICAL COMPOUND.

The Schedule referred to in these Letters Patent and making part of the same.

TO ALL WHOM IT MAY CONCERN:

Be it known that I, WILLIAM DAVIDSON, of Binghamton, Broome county, and State of New York, have invented a Composition for the Cure of the following Diseases: Rheumatism, Neuralgia, Sprains, Burns, Wounds, and Weak Backs. The same compound may also be used for horses for the following diseases: sprains, ring-bone, thoroughpin, curb, collar-gall, bruises, scratches, grease-heel, and thrush; and I do hereby declare that the following is a full, clear, and exact description thereof.

The nature of my invention consists in the preparation of a liniment composed of various chemical ingredients, compounded in such proportions as to act as a specific for the above-named diseases, to be known as "Davidson's Compound Oil."

I make my composition of the following ingredients in the proportion as given: Spirits of turpentine, one half pint; oil of spike, one half pint; oil of origanum, two ounces; oil of olive, two ounces; alcohol, four ounces; chloroform, one and a half ounce; pulverized alum, one half drachm; aqua ammonia, two ounces; saltpetre, one half ounce; oil of vitriol, two drachms.

I pulverize the saltpetre and alum and put them into a vessel, add the spirits of turpentine and the other ingredients with the exception of the vitriol, which I add in a slow and cautious manner, the action of which produces a chemical effect upon the entire mass.

Having thus described my invention, what I claim, and desire to secure by Letters Patent, is—
The composition herein described, for the purposes set forth.

WILLIAM DAVIDSON.
